FREQUENCY-CHANGING CIRCUIT

Charles Cecil Eaglesfield, Surrey, England, as signor, by mesne assignments, to Radio Corporation of America, New York, N. Y., a corporation of Delaware

Application June 13, 1939, Serial No. 278,814
In Great Britain October 26, 1938

3 Claims. (Cl. 178—5.8)

This invention relates to frequency-changing circuits employing electron discharge tubes and has for its object to provide an arrangement exhibiting high conversion conductance (and therefore suitable *inter alia* for television receivers) by making use of a secondary-emission tube, i. e. a tube incorporating a primary cathode, a control grid, a secondary emission electrode (hereinafter termed the auxiliary cathode) which gives off secondary electrons when bombarded with primary electrons, and an anode, with or without other electrodes such as a screen grid.

The invention is based on recognition of the fact that with a suitably constructed tube of this type oscillations may be produced, and the anode stream modulated accordingly, by coupling the control grid and the auxiliary cathode; in such a tube the alternating voltages of the control grid and auxiliary cathode are normally in phase and if a coupling circuit is provided between these electrodes so as to preserve or substantially preserve this relationship, (the phase agreement need not be at all exact) the tube will act as a generator of oscillations.

According to the present invention provision is made of a self-oscillating frequency-changer comprising a secondary emission tube provided with a coupling as described in the preceding paragraph, the signal input circuit being connected to the control grid, the oscillation generated being such as to modulate the anode stream at the desired heterodyne frequency, and the anode circuit being provided with an impedance from which the intermediate frequency is derived.

In order that the invention may be more readily understood reference will now be made to the embodiment thereof that is illustrated by way of example in the accompanying drawing.

The drawing shows a self-oscillating frequency changer for a television receiver comprising a secondary emission tube V. This tube has an indirectly heated cathode 1, a control grid 2, a screen grid 3, an auxiliary cathode 4 and an anode 5. The control grid 2 is connected to the input terminal 6 by way of a coupling condenser C₁ and the lower end of the bias resistance R₁ connected into the cathode lead is joined to the input terminal 7. Resistance R₁ is shunted by the usual by-pass condenser C₂. The grid-cathode circuit is shunted by a variable inductance L₁ which in conjunction with the grid-cathode capacity tunes the input circuit to the signal frequency. This arrangement offers the advantage

as compared with variable capacity tuning that high grid impedance at the heterodyne frequency is maintained.

10 The screen grid 3, the auxiliary cathode 4 and the anode 5 are connected to the positive side of the power supply by decoupling resistances R₂, R₃ and R₄ with which are associated decoupling condensers C₃, C₄ and C₅ respectively. The connection between the auxiliary cathode 4 and the associated decoupling resistance R₃ includes a parallel circuit of inductance L₂ and capacity C₆ tuned to the heterodyne frequency, e. g. 32 megacycles/sec. The end of this tuned circuit remote from the auxiliary cathode 4 is connected to the cathode 1 by a resistance R₅ and the inductance L₂ has a tapping, e. g. a central tapping which is connected to the control grid 2 by a condenser C₇ and a resistance R₆ in series. Since the grid 2 and auxiliary cathode 4 are in phase the coupling of these two electrodes by means of the resistance R₆ causes the tube to self-oscillate. The condenser C₇ is merely a blocking condenser to prevent the application of the high positive voltage to the grid 2.

25 The anode circuit includes the primary L₃ of a band-pass transformer across which the vision intermediate frequency is developed and a variable inductance L₄ across which the sound intermediate frequency is developed. The secondary L₅ of the band-pass transformer is connected to a terminal 8 from which the vision intermediate-frequency circuit is supplied while the inductance L₄ is connected through a coupling condenser C₈ to a terminal 9 from which the sound intermediate-frequency circuit is supplied. The input to the latter circuit is shunted by a condenser C₉. It is found that with a suitable choice of capacity values this arrangement permits the sound and vision intermediate-frequency circuits to be tuned independently of one another. The inductances L₃, L₅ are shunted by condensers C₁₀, C₁₁ and damping resistances R₈, R₉ respectively.

30 The voltage of the screen 3 should be appreciably lower than the lowest voltage to which the auxiliary cathode 4 swings.

35 With the above-described resistance coupling of the grid 2 and auxiliary cathode 4 the phasing at the heterodyne frequency indicated is theoretically incorrect for maintenance of oscillations but it is found that the circuit gives satisfactory results in practice and is simple to adjust. A circuit that produces a phase relation that is nearer to that which is theoretically the optimum is produced by replacing the resistance

R_6 by an inductance; this circuit may be appropriately used when the heterodyne frequency is lower than the signal frequency. Other forms of coupling may be used; for example, when the heterodyne frequency is higher than the signal frequency the coupling may be effected solely by a condenser. The connection to the circuit L_2 , C_6 may be effected at the end remote from the auxiliary cathode instead of at a tapping as shown.

The invention offers the advantage as compared with the use of a secondary emission tube operating as a dynatron oscillator that a circuit of high impedance is not required in the connection to the auxiliary cathode; furthermore since a high impedance circuit is not required we may use a circuit consisting of high C and low L whereby the behavior of the tube at frequencies other than the heterodyne frequency (in particular the intermediate frequency) is not appreciably affected by the insertion of the components necessary for self-oscillation.

I claim:

1. A frequency changer network comprising an electron discharge tube having at least a primary cathode, a signal input electrode, an auxiliary cathode and an anode, a signal input circuit connected between the input electrode and the primary cathode, a local oscillation circuit resonant to a frequency different from the signal input circuit connected between the auxiliary cathode and

the primary cathode, a path including an impedance connected between the input electrode and a tap on the inductance of the oscillation circuit, and an impedance included in the anode circuit from across which the intermediate frequency is derived.

2. A frequency changer network as defined in claim 1, wherein a screen grid electrode is interposed between the input electrode and the auxiliary cathode, said screen grid electrode having a potential impressed thereon which is lower than the lowest voltage to which the auxiliary cathode swings.

3. A frequency changer network comprising an electron discharge tube having at least a primary cathode, a signal input electrode, an auxiliary cathode and an anode, a signal input circuit connected between the input electrode and the primary cathode, an oscillation circuit resonant to a frequency different from the signal input circuit having its high potential end connected to the auxiliary cathode, a resistance connected between the low potential end of said oscillation circuit and the primary cathode, a circuit including a series resistance and a condenser connected between the input electrode and a tap on the inductance of the oscillation circuit, and an impedance included in the anode circuit from across which the intermediate frequency is derived.

CHARLES CECIL EAGLESFIELD.
